UNITED STATES PATENT OFFICE.

LUCY H. TAZZA, OF SAN FRANCISCO, CALIFORNIA.

CREMATION CASKET.

Application filed December 15, 1925. Serial No. 75,552.

My invention relates to improvements in caskets for cremation purposes wherein a casket is formed from compressed paper or other compressed combustible fibrous material and provided with removable hardware whereby the casket may be burned with a minimum of residue and with a minimum of waste.

In performing cremation, the practice has commonly been to place the body to be cremated in an elaborate and expensive casket of the type commonly used for burial purposes, the body and casket being placed in the cremation furnace and consumed together. Caskets of this type are made of relatively costly materials and construction and are provided with ornamental hardware of an expensive nature. The consuming of a casket of this form constitutes an economic waste as the combustible materials are of course entirely consumed and the hardware and fittings rendered unfit for further use. In addition the cost is so great as to be extremely burdensome upon persons whose means are limited.

In order to avoid this economic waste and to provide a cremation casket of relatively low cost I have devised my new and improved casket, the primary purpose of which is to provide, as a new article of manufacture, a casket formed from compressed paper whereby the casket can be produced at a very low cost and may be entirely consumed in the cremation process.

Another object is to provide an improved casket provided with removable hardware whereby said hardware may be removed before the casket is placed in the furnace and which may be used repeatedly.

A still further object is to provide an improved device of the character described whereby the hardware may be easily adjusted to caskets of various sizes, and readily applied and removed.

A still further object is to provide a device wherein detachable bands of flexible metal serve to secure the cover upon the casket and to form mountings for handles whereby the casket may be lifted and moved.

I accomplish these and other objects by means of the improved device disclosed in the drawings forming a part of the present invention wherein like characters of reference are used to designate similar parts

throughout said specification and drawings and in which,

Fig. 1 is a perspective view of my improved casket.

Fig. 2 is a transverse section through the casket.

Fig. 3 is a broken plan view of the overlapping ends of the securing bands.

Fig. 4 is a broken transverse section through the cover of the casket and the securing means, the figure being drawn upon a somewhat larger scale.

Referring to the drawings the numeral 1 is used to designate the body portion of a casket provided with a removable cover 2. The body and cover are formed from compressed paper or other suitable combustible fibrous material adapted to be molded, pressed, or otherwise shaped to form the casket.

A pair of flexible bands 3, preferably formed from flexible metal, are arranged to extend around the casket adjacent the ends thereof, the ends of said bands being arranged to overlap upon the top of the casket.

The overlying end of each band is provided with a pair of apertures 4 spaced apart a distance slightly less than the width of the top of the smallest casket to which the bands are to be applied. The underlying end of each band 3 is provided with a plurality of apertures 6 relatively closely spaced and so arranged that said apertures 6 will register in pairs with the apertures 4. The overlapping ends are secured together by means of

securing elements inserted and secured through the apertures 4 and a pair of the apertures 6, said securing elements preferably consisting of threaded stems 7 having base portions 8 arranged to be engaged between the underlying portion of the band and the top of the casket. Knobs 9 or other suitable members are tapped to be threaded onto the upwardly extending ends of the stems 7 to secure the bands in position around the casket.

Handles 11 of suitable size and form are mounted upon the bands 3 upon opposite sides of the casket whereby the casket may be lifted and moved. The handles are made adjustable upon the bands, preferably by

threading the bands through openings 12 formed in a base 13 upon which the handles are carried. By this construction the

handles may be readily moved to desired positions along the bands when said bands are extended and will bind upon the bands when an upward lifting force is applied to 5 the handles.

The bands 3, the knobs 9, and the handles 11 and bases 13, may be made of any desired ornamental appearance and finished in any manner suited to harmonize with the 10 purpose to which they are applied. The casket itself is shaped and finished in any suitable manner, preferably of a moderately ornate appearance and of rich finish conforming to the relatively elaborate forms 15 used in common practice.

The body is placed in the casket in the ordinary manner, and during the funeral services will present an appearance not materially different from the forms of caskets 20 heretofore used. While the cover is removed from the casket, the flexible bands 3 are turned outwardly and downwardly and held out of the way in any convenient manner. When the casket is closed, the bands are 25 extended upwardly around the sides of the casket and secured in overlapping relation as above described. The casket may now be readily lifted and moved by means of the handles 11 carried by the bands 3, the 30 weight being supported and carried upon the bands 3.

After the casket has been transported to the cremation furnace, the bands 3 are disengaged and removed from the casket. The 35 casket and the body therein contained is then inserted into the furnace in the ordinary manner and the cremation performed. The casket, being formed entirely of compressed paper, is readily and completely 40 consumed within the furnace. The hardware, consisting of the bands, securing members, and handles are however saved and may be used repeatedly.

The compressed paper construction provides a casket which can be constructed at a 45 relatively low cost, and as the casket does not require the rugged and resistant char-

acter required for caskets intended for purposes of burial, accomplishes its purpose as fully and effectively as the more costly forms 50 commonly used heretofore. In this manner the economic waste caused by the burning of costly caskets and expensive fittings may be entirely eliminated, and at the same time accomplish a material saving to the individual 55 purchaser.

The flexible metal bands and fittings, as above explained may be constructed of an elaborate form and of costly materials as said bands and fittings become permanent 60 equipment used repeatedly. The adjustable character of the bands and handles permits them to be applied quickly and easily to caskets of various sizes and shapes, thereby reducing the number of sets of such bands 65 necessary for use by the undertaking establishment or crematory.

While I have illustrated and described only one form and construction of my invention, it will readily be seen that the invention is subject to modification in numerous ways. I therefore do not wish to restrict myself to the specific details of construction disclosed, but desire to avail myself of all modifications which may fall 75 within the scope of the appended claim.

Having thus described my invention what I claim as new and desire to secure by Letters Patent is,

The combination with a cremation casket, 80 of a pair of flexible bands adapted to extend around the casket adjacent the ends thereof, said bands having a pair of spaced apertures formed adjacent one end and a plurality of closely spaced apertures formed 85 in the opposite end, said closely spaced apertures being adapted to register in pairs with the first mentioned apertures; and handles adjustably secured upon the bands and adapted to be held thereby upon opposite 90 sides of the casket whereby the casket may be lifted and moved.

LUCY H. TAZZA.
